UNITED STATES PATENT OFFICE

JACOB COLITZ, OF CHICAGO, ILLINOIS

WIRE DISPENSING APPARATUS

Application filed February 28, 1929. Serial No. 343,365.

My invention relates to wire dispensing apparatus of the type employed by electricians and like artisans, and more particularly to reels supported in a manner to feed the wire as required, and my main object is to provide a novel reel of this kind in which the wire coil is vertically positioned whereby to dispose the wire for handy removal.

10 A further object of the invention is to design the novel reel with means to firmly secure the wire coil against slippage or disintegration, and to support the same in a position to be rotated for the release of wire as required.

15 A still further object of the invention is to construct the novel reel with means to accommodate two coils of wire which are independently rotatable to feed one or two wires in separate courses.

20 Another object of the invention is to so design the novel reel that the mounting of the wire coil upon the same may be accomplished with ease and no appreciable loss of time.

25 A significant object of the invention is to construct the novel reel with a stand which is simple and compact, and may be moved about with ease to become located handy to the work.

30 An important object of the invention is to incorporate means in the apparatus whereby to lock the wire coils to the stand when the apparatus is not required for use, whereby to prevent theft of wire from the apparatus.

35 A final, but nevertheless important object of the invention is to design the stand of the reel with simple means for the proper guidance of the wires as required for the various phases of the work.

40 With the above objects in view and any others that may suggest themselves from the specification and claims to follow, a better understanding of the invention may be gained by reference to the accompanying drawings, in which—

Figure 1 is an end elevation of the apparatus;

45 Fig. 2 is a rear elevation, taken from the left hand side of Figure 1, of the stand,

showing only one end portion of the latter;

Fig. 3 is a plan section of the reel, showing provision made for two wire spools;

Fig. 4 is an end elevation of one of the reel units, partly broken away, and in receptive position for a coil of wire;

Fig. 5 is a view similar to Figure 4 showing the position changed for the retention of the coil of wire;

Fig. 6 is a detail elevation of a locking device;

Fig. 7 is a section on the line 7—7 of Figure 6; and

Figs. 8, 9, and 10 are views of detailed parts.

In running electric wire to conduits having the usual wall or ceiling outlets, the wire is usually taken from a coil which lies flat on the floor. As the wire from one or two coils is taken, spirals of the wire rise from the coil and often become tangled or snarled, requiring patient handling and straightening before the wire can be fed into the outlet. Also, the spiral form of the wire sections makes the wire hard to train and considerable time is lost by the worker in attending to the passage of the wire from the coil to the point where it is handled. By the use of the novel dispensing apparatus, I employ a reel in a single unit or in two units in a stand of skeleton type, such reel being movable with ease to any point desired, and maintaining the coils in a position to feed the wire as demanded and without spreading or tangling the same.

Referring specifically to the drawings, the stand which is employed to support the wheel is composed of crossed end units, formed of metal bars 15 and 16, the front of the stand being considered on the side of the upper portions of the bars 16. The bars 15 are joined at the top by a cross rod 17 which acts as a cross-brace and also serves as a handle to draw or push the stand wherever desired; and for facility in moving the stand over the floor, the lower ends of the bars 15 are equipped with ground wheels 18. The bars 16 are plain at their lower ends in order to maintain the stand with stability wherever set. Further cross-braces 17a and 17b are

provided at the lower portion of the stand.

The ends of the stand receive riveted plates 19, formed with outward and opposed bends 20 which are cut with open slots 20a to form

5 bearings for the end trunnions 21 of a solid shaft 22 designed to support the reel units. The bends 20 receive and are braced by cross

10 bolts 23 which are secured by nuts 24; and each end structure is provided with an arm

15 25 pivoted in the corresponding bar 15 to swing as indicated by dotted lines in Figure 1. The arm 25 has an aperture 25a in its free end which registers with an opening in

the upper end of the corresponding bar 16, so that when the arm moves alongside the bar

16 26 may be passed through the registering apertures to lock the arm to the bar. With this done, it will not be possible

20 to lift the trunnions 21 clear of the stand. However, when the arms 25 are swung up as

25 indicated by dotted lines, the removal of the trunnions may be effected, since their bearings are open at the top as indicated at

20a in Figure 2.

25 It is my intention that the reel units for each coil of wire rotate freely upon the shaft 22, so that wire may be drawn from each reel by causing the latter to spin. To this end,

30 I construct each reel unit fundamentally with end disks 27 and 28, these disks being circular in form and centrally apertured to freely turn upon the shaft. The disks 27 and 28

35 are held together by means soon to be made plain, but in order that the reel units may

not move along the shaft, I provide fixed collars 29 on the latter from both sides of

35 the disk 28, as clearly shown in Figure 3, thereby stationing the disk from travel along

the shaft.

40 The disks 27 and 28 are held together by spacer straps 30 of which three are shown equi-distantly arranged. About these straps

45 is a floating ring disk 31 intended to be the mate for the disk 28 for the purpose of receiving therebetween a coil of wire 32 which has

50 been sectionally shown by the use of dotted lines in Figure 3.

As is noted in Figure 3, the outer disk 27

55 of the reel unit is considerably smaller than the inner one 28 and the spacer straps 30 are accordingly inclined, so that the wire spool

32 may be placed from the outer end of the reel unit with facility to occupy the position shown, the ring disk 31 having, of course,

55 been removed while this was done and then replaced as shown.

The reel unit on the left-hand side of Figure 3 shows the condition just described, and it is my intention to secure the wire spool

60 to the reel unit, so that the latter may retain the spool by assuming the changed position shown in the unit on the right hand side of Figure 3. The securing action mentioned

65 is effected by an array of rods 33 grouped about the center of the reel unit and normal-

ly having the inclined position shown in the left hand unit. These rods have outward right-angled bends 33a, and their action is to be swung outwardly from the position at the left to the position at the right, whereby to expand against the inner periphery of the wire coil 32 to secure a firm hold on the latter and use the outer bends 33a as end retainers next outside of the ring disk 31. The retainers during their expansive movement thus serve to locate the ring disk in a central position to properly guard the wire coil. In installing the rods 33, I form the inner ends thereof with heads 33b and anchor such ends loosely in a ring 34 secured by bolts 33c to the spacer straps 30, twisting alternate portions 34a of the latter to transverse position in order to stiffen the ring. The other ends of the rods 33, are formed with outward extensions 33c terminating with bends 33d

80 85 in the direction of the shaft 22.

Referring more particularly to Figures 4 and 5 means are noted for simultaneously spreading the rods 33 to secure the hold upon

90 the wire reel 32. For this purpose, I provide a fork-shaped spider 35, whose pocket receives the shaft 22, so that the spider may be

95 said to be centered about the shaft. In addition, the spider is intended to be moved transversely of the shaft and in close proximity to the face of the disk 27, the latter having an external block 36 between the arms

35a of the spider and formed with flanges 36a to overlie the said arms and furnish

100 a guide for the movement of the spider. This movement from the position of Figure 4 to that of Figure 5 is effected by drawing an outward basal bend 35b of the fork in the corresponding direction. The bend 33d of

one of the rods 33 is secured to the fork bend 105 35b by being screw-threaded to receive a nut

37 inside the latter, and it will be obvious that with the outward movement of the fork the direct spread of the given rod 33 will occur.

As to the remaining rods, of which two 110 are employed laterally of the fork 35, links 38 are extended from the ends of the fork

arms 35 to be secured to the bends 33d of the corresponding rods by nuts 38a, the links being perforated for the loose passage of the

115 bends. The links 38 are longitudinally slotted as shown at 38b, to receive pins 39 outwardly extended from the disk 27 for

guidance; and spring 40 extended to the links

120 from the disks are employed to maintain the parts in the inactive position of Figure 4.

Thus, when the fork 35 has been moved to the position of Figure 5, the effect will be to spread all of the three rods 33 against the

125 tension of the springs 40, which, however, return the parts to the original position when they are released. The fork receives additional guidance by being cut with a slot 35b

through which a headed stud 35c is passed

130 into the disk 27.

When mounting a given wire coil, it is, of course, desirable that the same be clamped fast upon the reel unit in the manner described. In order that the clamping means may remain set, I provide a locking device illustrated in Figures 4 to 7. On the outer face of the disk 27 at a point to one side of the fork 35 is rockably mounted on a rivet pin 41 a key fitting 42, the same having oppositely directed tongues 42a and 42b. The tongue 42a is in a position directly in the way of the fork as it is shifted, and trips into a notch 43 in the nearer arm of the latter as the position of the fork is changed as shown in Figure 5. The disk 27 is perforated as indicated at 27a and 27b at laterally spaced points adjoining the site of the key fitting 42 to permit the outwardly projecting branches 44a and 44b of a rocker arm 44 behind the plate to emerge to the outer side of the disk as shown. The rocker arm 44 is mounted on a pin 45 for motion in a horizontal plane, the pin being supported by a tongue 46 forced in from the stock of the disk and leaving the aperture 46a. Owing to the greater weight of the tongue 42a, as against the tongue 42b of the key fitting 42, the tongue 42b normally bears up against the branch 44a. However, the tongue 42a is notched at 42c in the edge opposite the disk 27, so as to clear the branch 44a in case the position of the key fitting becomes inverted. It will now be seen that with the position of the fork 35 extended and the tongue 42a caught in the notch 43 of the fork, the latter will be prevented from returning by the abutting position of the tongue 42b against the rocker arm branch 44a. The rocker arm 44 is maintained in the position shown by an expansive spring 47 effective upon the branch 44b. The locking effect upon the wire coil is thus maintained. However, should it be desired to release the clamping means for the coil, it is only necessary to draw upon the branch 44b by means of a handy finger ring 44c, this swinging the rocker arm 44 with the effect of backing its branch 44a off the tongue 42b. The springs 40 drawing upon the fork 35 will now cause the same to return to the initial position. It should be noted that the notch 43 in the fork is of extra width so as to permit angular motion of the tongue 42a for the entrance and release thereof.

In cases where but a single reel unit is necessary, the structure may be considerably simplified by substituting for the arrangement of the trunnions 21 the simple cross piece 48 shown in Figure 10. Two of these cross pieces are slid upon the shaft 22 near the ends and the points 48a of the cross piece made to serve in the manner of the trunnions 21 by seating the same in the slots 20a of the frame bearings.

The stand of the reel is equipped with special guiding units for the wire as it is

drawn from either or both reel units. Thus, where the wire is drawn downwardly, as indicated by dotted lines 49 in Figure 1, for the leading of the wire downwardly by way of the outlet 50 into the lower conduit 51, it is 70 desirable to have a cross rod 52a in front to guide the wire. This cross rod is supported by side pieces 53 secured to the ends of the stand. On the other hand, where it is desirable to feed the wire upwardly by way of 75 the outlet 50 into the upper conduit 52', the wire is first led down as indicated by dotted lines 54 to wrap under a cross rod 55 and to continue in an upward direction into the outlet and further into the conduit 52. Like the 80 rod 52a, the second rod 55 is also suitably supported by side pieces 56 secured to the ends of the stand. Frequently, it is desirable to raise the wire high to feed it in a downward direction to a high wall outlet, in which event 85 the benefit of a cross rod 57 is had, this rod being held by side pieces 58 which swing as a unit from pivotal supports 59 near the upper ends of the stand bars 15. Thus, in order to make use of the cross rod 57 for the guidance of a given wire or wires, the assembly of 90 the rod and its side pieces 58 is swung in the direction of the small arrow in Figure 1 to the position indicated by dotted lines. In order that the arch so formed may remain as 95 swung, I provide a simple locking device, constructed as follows:—The bars 15 are provided at their upper ends with forwardly projecting keeper plates 60, and each of the side pieces 58 carries in swiveled relation at 100 61 a plate 62, this plate having an inward bend 63 at one end and an outward lug 64 projecting from one of its sides. When the arch is not used, the weight of the bend 63 maintains the plate 62 in the position shown in Figures 1 and 8, the lug 64 of each plate abutting the forward edge of the corresponding side piece 58. However, when the arch has been swung to the high position, the plate 105 over-balances due to the weight of the bend 63, so that the bend assumes a position in front of the frontal edge of the keeper plate 60 and is prevented from falling below such edge by the stopping of the lug 64 against the rear edge of the side pieces 58. Thus, any 110 rearward stress on the part of the raised arch is counteracted by the pressure of the bends 63 upon the forward edges of the keeper plates 60.

When it is necessary to confine a wire or wires to a fairly definite course, the device illustrated in Figures 2 and 9 may be employed. This device consists of two major parts. One of these is a tubular clamp 65 which is mounted on the stand rod 17, and whose jaws 65a are secured by thumb screws 66 whereby to secure the clamp yet leave a space between the jaws. In this space is insertable the terminal stem 67a of a wire loop 67, whose opposite terminus is formed with 125 130

an eye 67b which is loosely linked on the rod 17. When the loop 67 is slid in the direction of the clamp 65, the stem 67a may be rested upon the inner one of the thumb screws 66, the loop 67 serving as an enclosure for the passage of a wire therethrough. In order that the departure of the loop 67 from the clamp may be counter-acted, a third thumb screw 68 is applied to the jaws on the inner 10 side of the stem 67a, as indicated in Figure 2, so that it will be impossible to back the stem out of the clamp. The latter is accordingly fixed upon the rod 17, but it is easy to open the loop 67 at any time, this being done 15 by simply turning the thumb screw 68 to a sufficient extent that the stem 67a may clear the same when the loop 67 is slid in a departing direction from the clamp.

Besides having a bracing function for the 20 plate bends 20, the bolts 23 also serve as leaning supports for the shaft 22 when it is swung high at one end with the corresponding set of trunnions 21 as a pivot, so as to rest against the proper bolt 23 and facilitate the mounting 25 of a wire coil by way of the free end of the shaft. Further, I provide a cross-piece 23a more inwardly of the bends 20 to serve as a catch support in case such free end of the shaft fails to reach the leaning support 23 30 and is about to drop. By stopping the shaft as a medial point in its fall, the cross-piece 23a saves the free end of the shaft and parts associated therewith from suffering injury or distortion by heavily striking parts in the 35 lower portion of the stand.

It will be seen that I have provided a structure of rugged design and extreme simplicity to accomplish the purposes I have in mind. The entire device is of comparatively 40 light metal, and may be readily drawn from one place to another to be handy to the outlet services. By placing the reel units on a horizontal axis and away from the floor, I keep the accumulation of wire in the coils in the 45 closely wound relation in which it comes and only remove as much wire as is required. Finally, the device is simple to handle and operate, and will save a great deal of time, labor and difficulty to the worker.

50 I claim:—

1. A wire reel comprising a frontal disk, a backing disk, and a circular array of spaces rigidly connecting the disks and adapted to receive the wire coil, one disk being larger 55 and the spacers tapering in a conical assembly in the direction of the other disk, and means carried by the disks and expansible against the inner side of the coil to hold the latter to the disks.

60 2. The structure of claim 1, and outward guards extended from said means to confine the coil between the guards and the backing disk.

65 3. The structure of claim 1, outward guards extended from said means to confine the coil

between the guards and the backing disk, and intermediate disks lining said guards and serving as outer walls for the coil.

4. A reel for wire coils comprising a frontal disk, a backing disk, spacers to rigidly connect the disks and receive the wire coil, a ring carried by the spacers inwardly of the backing disk, a circular array of rods linked with their rear portions to the ring, and means carried by the frontal disk to 70 spread and gather the rods.

5. A wire reel comprising a spool-like body adapted to carry a wire coil, circularly-grouped members carried by the body to hold the coil to the same, a lever reciprocable on one end of the body to operate one of said members radially, and links extended from said lever to operate the other members radially, the member-group expanding with 80 one directional movement of the lever and links and contracting with the opposite movement thereof.

6. The structure of claim 5, and springs effective upon the links to resist the expansive movement of the member-group. 90

7. The structure of claim 5, and an automatic lock effective on the lever when moved to a position whereby the expansion of the member-group is attained.

8. The structure of claim 5, and a shaft on 95 which the body is rotatable, the lever being bifurcated in the region of the shaft to clear and be guided by the same.

9. A wire reel comprising a spool-like body adapted to carry a wire coil, expansible means carried by the body to hold the coil to the same, an outwardly movable lever on one end of the body to operate said expansion means and recessed on the side, a rockable detent tripped by the outward movement of the lever and received in the recess of the latter, and a stop to check the detent when urged by the inward movement of the lever, whereby to lock the latter again inward motion. 110

10. The structure of claim 9, the detent being on the face of said end, and the stop protruding from behind the latter.

11. The structure of claim 9, the detent being on the face of said end and the stop protruding from the latter, and pressure means to maintain the stop in effective position. 115

12. The structure of claim 9, the detent being on the face of said end and the stop protruding from the latter, pressure means to 120 maintain the stop in effective position, the stop being rockable to and from said position, and an extension of the stop manually operable to rock the latter in a direction to dispose it in the ineffective position.

13. A wire reel comprising a spool-like body, a shaft on which the latter is rotatable, stops on the shaft to check the endwise travel of the body, laterally-extended trunnions carried by the ends of the shaft, open bear- 125

ing standards to receive the trunnions, and terminal cross rods carried by the bearing standards and forming leaning stops for the shaft when poised in one of the bearings.

- 5 14. A wire reel comprising a spool-like body, a shaft on which the latter is rotatable, stops on the shaft to check the endwise travel of the body, laterally-extended trunnions carried by the ends of the shaft, open bearing standards to receive the trunnions, and cross rods carried inwardly by the bearing standards and forming catch stops for the shaft when the shaft fails of support in one of the bearings.
- 10 15. A wire reel comprising a spool-like body, a shaft on which the latter is rotatable, stops on the shaft to check the endwise travel of the body, laterally-extended trunnions carried by the ends of the shaft, open bearing standards to receive the trunnions, and hasps adapted to close over the shaft end-portions and confine the shaft in the bearings.
- 15 16. The structure of claim 15, and locking devices to secure the hasps to the bearing standards.

In testimony whereof I affix my signature.
JACOB COLITZ.
